(57) **CLAIM**

The ornamental design for a package for cosmetic products, as shown and described.

DESCRIPTION

FIG. 1 is a perspective view showing a new design;

FIG. 2 is a front view of the new design;

FIG. 3 is a rear view of the new design;

FIG. 4 is a right side view of the design;

FIG. 5 is a left side view of the design;

FIG. 6 is a top view of the new design; and,

FIG. 7 is a bottom view of the new design.

The broken lines are included for the purpose of illustrating portions of the packaging for cosmetic products that form no part of the claimed design.
